UNITED STATES PATENT OFFICE.

HENRY A. S. STAHL, OF LONG ISLAND CITY, NEW YORK.

DESIGN FOR A VIOLIN.

Application filed October 11, 1922. Serial No. 3,943. Term of patent 7 years.

To all whom it may concern:

Be it known that I, HENRY A. S. STAHL, a citizen of the United States of America, residing at Long Island City, in the county of Queens and State of New York, have invented a new, original, and ornamental Design for a Violin, of which the following is a specification, reference being had to the accompanying drawing, forming a part hereof.

In the drawing:

Fig. 2 is a plan view of the same.

I claim:

The ornamental design for a violin as shown.

HENRY A. S. STAHL. [L.S.]
